United States Patent Office.

L. W. LATHROP, OF NYACK, NEW YORK.

Letters Patent No. 97,935, dated December 14, 1869.

IMPROVEMENT IN SEWING-MACHINE.

The Schedule referred to in these Letters Patent and making part of the same.

To all whom it may concern:

Be it known that I, L. W. LATHROP, of Nyack, in the county of Rockland, and State of New York, have invented a new and useful Improvement in Sewing-Machines; and I do hereby declare that the following is a full, clear, and exact description thereof, which will enable others skilled in the art to make and use the same, reference being had to the accompanying drawings, forming part of this specification.

This invention relates to improvements in sewing-machines, and consists in certain improvements in mechanism for forming the loop, and for conveying the binding-thread through the same, in a manner to prevent the contact of the binding-thread spool, or its carrier, with the thread of the needle, and thereby to avoid wearing the same, and to produce more easily-operating parts; also a more permanent and reliable arrangement of apparatus, and calculated also to be more certain to form the stitch.

Figure 1 represents a side elevation of a sewing-machine constructed according to my improvements, a part of the table being shown in section;

Figure 2 represents a transverse section of the table and front elevation of the operating-devices;

Figure 3 is a partial side elevation showing the position of the looper when the spool is passing through the loop; and

Figure 4 is a detail in plan view, also taken when the spool is passing through the loop.

Similar letters of reference indicate corresponding parts.

The needle-operating devices, presser, and feed-devices, are of common construction, and need not, therefore, be described.

I provide a pendent plate, A, with a groove in its face, standing in the vertical plane, or nearly so, of the axis of the driving-shaft B, in which groove the needle C works, and is supported throughout its length below the table; and to the bottom of this plate, which extends below the lowest position of the point of the needle, I pivot a bent looper, D, having a thin-edged lip, E, arranged so that when the needle is down it will, on the looper being vibrated past the needle, pass sufficiently above the eye, and so closely against the needle, as to go between the thread and the needle into a groove in the outer curved face of the said looper. A top view of this groove is seen at P, fig. 2.

This looper is then moved back in this way past the side of the needle, by a cam, G, on the disk-wheel H, on the end of the shaft B, working against the ends of a push-rod, I, connected to the end of the looper below its pivot, forcing the said looper back into the position represented in fig. 3, thereby forming a large loop for the passage of the spool K, carrying the binding-thread.

This spool is mounted on journals in bearings L, rising up from a rod, L', arranged to slide in the slotted tubular way N, consisting of a slotted tube with a vertical flange or plate projecting below, and suspended transversely of the machine in any suitable way. It is notched at O, to provide room for the looper, in moving back, to form the loop.

This spool-carrier is moved back and forth by the notched slide M, working on the way N, and operated by the slotted vibrating-arm P, in which a pin, R, of the disk H works.

At S it is connected to a projection, T, of the slide M.

The cam G, by which the looper is forced back, terminates in a flange V, parallel with the face of the disk, and extending part of the way around the same, it holds the looper in the position to which it is moved, until the spool passes through the loop, immediately after which the said flange passes beyond the push-rod I, when the retracting-spring V instantly throws it back again to the position represented in fig. 1, ready for the next operation. While it stands in this position, waiting for the needle to come down again, the spool-carrier returns to the position at the right, as seen in fig. 2, ready for passing through the loop when the looper is again moved by the cam G.

As soon as the needle has descended to its farthest point below the fabric, and formed a sufficient loop to be seized by the looper, the said looper being grooved or lipped on its outside curve, moves backward and takes hold of this needle-loop, extending and carrying it back sufficiently for the free passage of the spool and its carrier through the loop, and on the inside of the curved looper.

The looper, in this movement, presses against the end of the spool-holder, so as to push it away from contact with its driver during said passage. The driver now pushes the spool-holder with its spool through this needle-loop, leaving a bight of its thread inside of the needle-loop.

The needle remains stationary during those movements, the looper also holding the needle-loop stationary during the passage of the spool, and forms a shield between the needle, thread, and the under spool.

The looper now moves forward beyond the needle, again pressing a free passage between the spool-holder (it having returned to its first position) and its driver. The needle now carries a portion of its loop above the fabric, and returns with its thread after the fabric has been fed along by the feeding-arrangement, and again presents the needle-thread to the looper, which again moves backward with the needle-loop as before, forming this loop out of the former loop, except so much as has made the length of the previous stitch, this much having been drawn through the needle-eye. This movement of the looper completely tightens the

former stitch, so that each stitch is made without unnecessary "take-ups" above the fabric, or the friction against either a bobbin-spool case or shuttle, as in other shuttle-stitch machines.

It will be seen that in this way the thread is tightened up in the stitches without the aid of any take-up devices, and thereby it encounters very much less wear and friction, and is consequently much less liable to break, and retains its full strength.

It will also be seen that the loops may be made large enough to pass large commercial spools of binding-thread through them, and that such spools may be used, thereby saving the labor of rewinding.

The thread of the binding-spool K is carried through a guide-eye in a bar, W, connected to the bearings L, and extending from one to the other behind the spool.

The movement of the spool-carrier being imparted by walls in the slide M, the said carrier will naturally rest at the end of each movement against the wall by which it has been pushed along, thereby closing the passage necessary for the looper in moving from side to side of the spool. I have, therefore, provided for shifting the spool and carrier along the slot, in the slide (the said slot being wider than the length of the carrier,) by the action of the looper on the carrier, in striking against the curved projection x of the bar W, when going behind the spool, and against the corner x' in coming forward.

I do not claim the formation of the shuttle-stitch by carrying the needle-thread over the under thread or spool; neither do I claim the use of the under-looper when it takes its loop on its inside curve, such having been done before; but

What I do claim as of my invention, and desire to secure by Letters Patent, is—

1. The combination of the grooved vibrating looper D and its actuating-cam, with the open spool-carrying frame, having its ends bevelled, and against which ends the looper operates, as described.

2. The combination of the grooved vibrating looper and open spool-carrying frame, having bevelled ends, and constructed and operating together as described, with the way N, having the opening O for the passage of the looper, all substantially as described.

3. The arrangement of the needle-guiding plate, the grooved vibrating looper, the slotted way through which the looper vibrates, and the shuttle-carrying frame, when all are constructed as described.

The above specification of my invention, signed by me, this 4th day of September, 1869.

L. W. LATHROP.
